UNITED STATES PATENT OFFICE.

JULIA STABLER, OF NEW BRUNSWICK, NEW JERSEY.

DESIGN FOR A RUG.

Application filed March 4, 1927. Serial No. 20,963. Term of patent 7 years.

To all whom it may concern:

Be it known that I, JULIA STABLER, a citizen of the United States, residing in New Brunswick, Middlesex County, New Jersey, have invented a new, original, and ornamental Design for a Rug, of which the following is a specification, reference being had to the accompanying drawing, of which the single figure is a face view of a completed rug embodying my design.

I claim:

The ornamental design for a rug substantially as shown.

JULIA STABLER.
